ARCHITECTURAL FRETWORK

Jacob G. Braun, 3025 Old Glenview Road, Wilmette, Ill.

Filed Mar. 16, 1965, Ser. No. 84,290

Term of patent 14 years

(Cl. D54—2)

FIG. 1 is a front elevational view of an architectural fretwork embodying my new design, it being understood that the design is repeated as indicated;

FIG. 2 is a sectional view taken along the line 2—2 of FIG. 1, looking in the direction of the arrows; and

FIG. 3 is a sectional view taken along the line 3—3 of FIG. 1, looking in the direction of the arrows.

The appearance of the opposite sides of the design is the same as that of the face thereof illustrated in FIG. 1.

The broken lines on the drawing are disclosed for illustrative purposes only.

I claim:

The ornamental design for an architectural fretwork, substantially as shown and described.
